UNITED STATES PATENT OFFICE

163,387

COMBINATION CAN AND BOTTLE OPENER

Baraket L. Herro, Milwaukee, Wis.

Application January 24, 1950, Serial No. 7,455

Term of patent 14 years

(Cl. D22—2)

To all whom it may concern:

Be it known that I, Baraket L. Herro, a citizen of the United States, residing at Milwaukee, in the county of Milwaukee and State of Wisconsin, have invented a new, original, and ornamental Design for a Combination Can and Bottle Opener, of which the following is a specification, reference being made to the accompanying drawing forming a part thereof:

I claim:

The ornamental design for a combination can and bottle opener, as shown.

BARAKET L. HERRO.
